UNITED STATES PATENT OFFICE

119,330

DESIGN FOR A SHOE

Mortimer C. Seaman, Long Island, N. Y.

Application November 18, 1939, Serial No. 88,350

Term of patent 3½ years

To all whom it may concern:

Be it known that I, Mortimer C. Seaman, a citizen of the United States of America, residing in Long Island, county of Queens, and State of New York, have invented a new, original, and ornamental Design for a Shoe, of which the following is a specification, reference being had to the accompanying drawing, forming part thereof,

Fig. 1 is a plan view of a shoe showing my new design.

Fig. 2 is a side elevational view thereof.

I claim:

The ornamental design for a shoe, substantially as shown.

MORTIMER C. SEAMAN.
